United States Patent Office

Des. 206,887
Patented Feb. 7, 1967

206,887

DOLL

Enrique Bernat Fontlladosa, 184 Paris St.,
Barcelona, Spain

Filed Jan. 24, 1966, Ser. No. 726

Term of patent 14 years

(Cl. D34—4)

FIG. 1 is a front elevation view of the doll showing my new design;

FIG. 2 is a rear view thereof;

FIG. 3 is a top plan view thereof;

FIG. 4 is a right side elevation view thereof; and

FIG. 5 is a left side elevation view thereof.

I claim:

The ornamental design for a doll, as shown.
